UNITED STATES PATENT OFFICE.

FRANCIS M. VAN WORMER, OF SANDY HILL, NEW YORK, ASSIGNOR TO THE
SANDY HILL IRON AND BRASS WORKS, OF SAME PLACE.

PAPER-MAKING MACHINE.

SPECIFICATION forming part of Letters Patent No. 459,351, dated September 8, 1891.

Application filed March 14, 1891. Serial No. 385,036. (No model.)

To all whom it may concern:

Be it known that I, FRANCIS M. VAN WORMER, a citizen of the United States, residing at Sandy Hill, county of Washington, and State 5 of New York, have invented certain new and useful Improvements in Paper-Making Machines, of which the following is a specification.

My invention relates to such improvements; 10 and it consists of the novel construction and combination of parts hereinafter described and subsequently claimed.

Reference may be had to the accompanying drawings and the letters of reference 15 marked thereon, which form a part of this specification.

Similar letters refer to similar parts in the several figures therein.

Figure 1 of the drawings is a view in side 20 elevation of a portion of a Fourdrinier paper-machine, showing one end of the vibratory or shaking frame which supports the wire web or belt and dekle-frame. Fig. 2 is a central vertical longitudinal section of a movable 25 frame for supporting the breast-roll when detached from the vibratory frame, showing a portion of the shake-posts in elevation and of a like frame to receive the roll when removed from the machine, located outside of the vibratory frame.

Referring to Fig. 1 of the drawings, A A are the shake-posts which support the breast-roll A'. The endless wire belt A² passes around the breast-roll and over the small rolls A³ to the usual couch-rolls. (Not shown.) The small rolls A³ are supported by frame A⁴, pendent from the shake-rail A⁵.

Assuch machines have been heretofore constructed the breast-roll bearings, when se- 40 cured to the shake-posts, were located on their front side, so that the posts came between the breast-roll and the couch-rolls, and to introduce a new wire web or belt or to remove the old one from the rolls for repairs or for any 45 other purpose it was necessary to remove the dekle-frame A⁶, which is very heavy and difficult of adjustment, and to lift the breast-roll from its bearings upward and rearward to the position occupied by the dekle-frame 50 to give the wire the slack necessary to remove and insert the roll. The wire belt is

frequently, if not generally, from nine to ten feet wide, while the distance from the breast-roll to the couch-rolls is about twenty feet, and very little lateral movement can be given 55 to so wide a belt obliquely to its line of travel between such rolls. Consequently one of the supporting-rolls must be withdrawn from the line of the belt and inserted within the belt endwise from one side of the belt. Usually 60 the belt is folded or rolled up and a fold slipped on over a couch-roll. Then the dekle-frame and small rolls are removed, the belt straightened out toward the breast-roll, the latter roll lifted from its bearings and inserted within the belt and then returned to 65 its bearings. It was necessary to remove the dekle-frame because the bearings of the breast-roll, being located on the front side of the shake-posts and its journals projecting out beyond such posts the roll could not be moved toward the couch-rolls to get the necessary slack in the belt without lifting the roll up over the posts into the place occupied by a portion of the dekle-frame. 70 The journals of the breast-roll are made long to project beyond their bearing-boxes to provide means for lifting the roll from its bearings, long pipes or tubes being slipped on over the journals by which the roll 75 is lifted. I have ascertained that by locating the breast-roll on the back side of the shake-posts, which is the side facing the couch-rolls, I am able to lift the breast-roll from its bearings and move it toward the couch-rolls to 80 slacken the wire belt without disturbing the dekle-frame or any of the parts above the shake-rails. The journals B of the breast-roll are supported by bearing-boxes B', resting upon the brackets B². The boxes are 85 detachably secured to the brackets by bolts B³, passing through lugs B⁴, one on the box and one on the bracket. The brackets are vertically adjustable upon the shake-posts, being secured thereto by a nut and bolt B⁵ in the 90 slot B⁶ and resting upon the adjusting-screw B⁷, rotary in the screw-threaded lug B⁸.

A frame C is erected from the floor on each side of the machine substantially in line with the shake-posts, each frame comprising a pair 95 of uprights C' and a fixed connecting cross-bar C² near the floor. The uprights are adapt-

ed to support on their upper ends the detachable cross-bar C³. The fixed cross-bars C² are adapted to support a detachable roll-supporting frame C⁴. This frame is provided with a series of concaved rolls C⁵, each having trunnions C⁶, provided with bearings located in the frame C⁴. The frames C are preferably permanently located in the position shown, being secured to the floor by bolts; but when desired the bolts may be removed and the frames detached from the machine.

To remove the breast-roll from within the wire belt, the rolls A³, supported by the shake-rail frame A⁴, are first removed and the journal-boxes detached from the brackets by removing bolts B³. The roll is then lifted one end at a time and the boxes removed from the brackets, which allows the journals to be lowered upon the brackets. The roll is then rolled back until the journals rest upon the detachable cross-bars C³. Sufficient slack is thus given the wire belt, as shown by the dotted lines in Fig. 1, to permit the roll-frame C⁴ and rolls to be placed on the fixed cross-bars C² between the wire and the breast-roll in the position shown in Figs. 1 and 2. The detachable cross-bars are then removed and the roll lowered upon the rolls C⁶, as shown in Fig. 2, after which the breast-roll is drawn out upon the portable roll-frame C⁷, having the rolls C⁸, as indicated by dotted lines in Fig. 2. The rolls C⁶ and frame C⁴ are then removed from the fixed cross-bars C², leaving the wire belt free to be rolled up and taken away. The machine can then be supplied with a new belt by placing the belt in the position indicated by the dotted lines in Fig. 1, inserting the rolls and frame C⁴ within the belt upon the fixed cross-bars, and pushing the breast-roll back upon such rolls between the same and the upper part of the belt, then lifting the breast-roll, placing the detachable cross-bars beneath its journals upon the supporting-uprights, removing the roll-frame C⁴ and rolls C⁶, rolling the breast-roll forward until its journals rest upon the supporting brackets, lifting the roll and securing the

journal-boxes in place beneath the journals, and then replacing the rolls supported by the shake-rail frame. I am thus able to easily and quickly substitute a new for an old wire belt without the delay and labor incident upon removing and readjusting the dekle-frame and connecting parts, which require very careful adjustment.

In small machines or with a sufficient number of attendants the breast-roll can be removed from or inserted in the slackened wire belt by lifting the same in and out; but I prefer to make use of a detachable track or way, as the frame C⁴ and rolls C⁵, inserted between the breast-roll and wire belt, upon which the roll can be moved out of and into the belt, substantially as hereinbefore described.

The portable way consisting of frame C⁷ and rolls C⁸ affords a convenient support for the breast-roll after the same is withdrawn from the belt; but any form of support may be provided, or the roll may be supported by attendants while the belt is changed.

What I claim as new, and desire to secure by Letters Patent, is—

1. In a Fourdrinier paper-making machine, the combination, with the wire-supporting breast-roll and roll-journals, of a pair of shake-posts and roll-supporting journal-boxes detachably secured to such posts on their rear side, whereby the breast-roll can be detached from the shake-posts and moved rearwardly for the purpose of giving slack to the wire belt, substantially as described.

2. In a Fourdrinier paper-making machine, the combination, with the wire-supporting breast-roll and roll-journals, of a pair of shake-posts, roll-supporting journal-boxes detachably secured to such posts on their rear side, a detachable way for such roll, and a pair of way-supports located in the rear of the shake-posts, substantially as described.

In testimony whereof I have hereunto set my hand this 7th day of March, 1891.

FRANCIS M. VAN WORMER.
